UNITED STATES PATENT OFFICE

WILLIAM J. MONTGOMERY, OF COLUMBUS, OHIO, ASSIGNOR TO THE JEFFREY MANUFACTURING COMPANY, OF COLUMBUS, OHIO, A CORPORATION OF OHIO

CENTRIFUGAL FAN

Application filed July 11, 1927. Serial No. 204,803.

The present invention relates to certain new and useful improvements in centrifugal fans, of the type adapted to revolve at relatively high speed for the generation of relatively high air pressure at the discharge opening of the casing.

The especial object of this invention is to provide, in a fan of the class described, means to prevent regurgitation of the air at the inlet of the fan wheel.

The means whereby I obtain this object are fully set forth in the following specification and illustrated in the accompanying drawings of which

Fig. 1 is a side elevation of a fan of the type to which my present invention relates.

Fig. 2 is a sectional view of the fan casing illustrated in Fig. 1 taken along the central vertical axial plane of the fan wheel.

Fig. 3 is a fragmentary sectional view on an enlarged scale taken in the same plane as Fig. 2.

Fig. 4 is a transverse sectional view of the fan wheel taken along the line IV—IV of Fig. 3.

Like numerals refer to similar parts in the several figures.

In the drawings the numeral 1 refers to a casing of the usual scroll type having parallel plain end walls 2 which are provided with concentric circular inlet orifices 3. The casing 1 is also provided with a tangentially disposed outlet funnel 4. Suitably supported in alignment with the axis of the inlet orifices 3 are the journal bearings 5 wherein is supported the shaft 6 perpendicular to the end walls 2. To the shaft 6 is fixed a hub 7 having an extension flange 8, preferably positioned centrally of the casing, and to this flange 8 are fixed the fan blades 9. The fan blades 9 project at both sides of the flange 8, parallel with the shaft 6 and their outer ends are fixed to the annular end plates 10 by which the blades are braced together to form a rigid wheel.

The service for which this fan is especially designed calls for relatively high static air pressure in the discharge funnel 4. To produce such pressure the fan wheel normally revolves at relatively high speed, and to fur-

ther increase this static pressure in the discharge funnel, the end plates 10 are inclined inwardly, forming truncated cones by which the outflowing current of air is concentrated near the medial plane of the casing. Due to this construction there is a relatively wide dead air space adjacent the walls 2 at each end of the casing, which, due to the great difference in pressure between the discharge funnel and the inlet orifices, tends to produce regurgitation of the air at the inlet orifices of the fan wheel. To overcome this difficulty I have provided, at the inlet orifices of the casing, the outwardly projecting conical flanges 11 which serve as funnels to guide the inflowing air currents. These funnels are extended inwardly by the cylindrical flanges 12 which guide the air currents to the fan wheel. Projecting outwardly from the inner edges of the end plates 10 are cylindrical flanges 13 which extend outside of and well beyond the inner ends of the flanges 12 and parallel thereto. To the flanges 13 are adjustably fixed, in any suitable manner as by the bolts 14 extending through axially extending slots therein, the sealing strips 15 of such width as to contact with the inner surfaces of the end walls 2 of the casing. The strips 15 thus form tubular gaskets and are composed of flexible fabric material of such character as to rub upon the inner surfaces of the end walls 2 without material friction, and to withstand the wear occasioned thereby. When the sealing strips become so worn as to break the seal between the fan wheel and the casing, the attachment bolts 14 may be loosened and the strips 15 adjusted to restore contact with the casing. The flexible fabric or equivalent material of elements 15 constitutes an anti-friction material as opposed to metallic material.

By the construction above described the air in the dead air spaces at the ends of the fan casing is effectively sealed off from the inlet orifices, thereby preventing regurgitation and greatly increasing the efficiency of the apparatus.

What I claim is:

1. In a device of the class described, a casing element, a rotor element in the casing ele-

ment having a tubular axial inlet member, said casing having a side wall normal to the rotor axis and provided with an inlet opening coaxial with the rotor, a tubular gasket of anti-friction material surrounding said tubular inlet member and axially adjustable thereon to form a sealing contact with the casing side wall marginally of the latter's inlet opening, and removable means securing the gasket to the tubular inlet member.

10 2. In a device of the class described, a casing element, a rotor element in the casing element having a tubular axial inlet member, said casing having a side wall normal to the rotor axis and provided with an inlet opening coaxial with the rotor, a tubular gasket of anti-friction material surrounding said tubular inlet member and axially adjustable thereon to form a sealing contact with the 15 casing side wall marginally of the latter's inlet opening and removable means securing the gasket to the tubular inlet member, said casing having an outlet opening through which said removable means is accessible.

20 3. In a device of the class described, a casing element, a rotor element in the casing element having a tubular axial inlet member, said casing having a side wall normal to the rotor axis and provided with an inlet opening coaxial with the rotor, a tubular element fixed 25 in said inlet opening and extending within said inlet member, a tubular gasket of anti-friction material surrounding said inlet member and axially adjustable thereon to form a sealing contact with the casing side wall marginally of the latter's inlet opening, and removable means securing the gasket to said inlet member.

40 4. In a device of the class described, a casing element, a rotor element in the casing element having a tubular axial inlet member, said casing having a side wall normal to the rotor axis and provided with an inlet opening coaxial with the rotor, a tubular element 45 fixed in said inlet opening and extending within said inlet member, a tubular gasket of anti-friction material surrounding said inlet member and axially adjustable thereon to form a sealing contact with the casing side 50 wall marginally of the latter's inlet opening, and removable means securing the gasket to said inlet member, said casing having an outlet opening through which said removable means is accessible.

55 5. In testimony whereof I have hereunto set my hand.

WILLIAM J. MONTGOMERY.
